UNITED STATES PATENT OFFICE

ERNEST ALFRED BOWLER, OF SOUTH GEELONG, VICTORIA, AUSTRALIA

AUTOMATIC GUN FOR RECORDING ON A TARGET THE RESULT OF SIGHTING
AND FIRING

Application filed April 30, 1930, Serial No. 448,699, and in Australia May 3, 1929.

This invention relates to dummy rifle apparatus for practicing marksmanship and has as its object to enable the recording on a target the result of a "hit" obtained by "sighting" and "firing" a rifle the use of the rifle being controlled by token or coin freed mechanism incorporated with the trigger of said rifle.

In apparatus according to the invention certain features are provided with a view to permitting use of the apparatus for the simple registration of the effective result of a "shot", and to permitting the freeing of the apparatus for operation by a coin or token as well as to permitting of adjustment by an operator of the degree of accuracy with which the artificial target registers the result of a "shot".

The invention apprehends the use of a dummy rifle which has incorporated therewith token or coin freed trigger mechanism and is rockably mounted on a suitable support with a rod or bar depending therein from said rifle and actuating a sweeping contact disposed above a contact plate, comprising a number of insulated sections, means combined therewith for illuminating any one of a series of lamps in a target, means for making contact to light any lamp when the trigger of the said rifle is pulled, means for adjusting the sweep of the contact point and means for retarding the opening of a contact after the said trigger has been operated to record a "shot" upon the target.

In order to more readily understand the invention, reference will now be made to the accompanying drawings in which:—

Figure 1 is a sectional view of the invention.

Figure 2 is a view showing more particularly the trigger and lever movement and the means of operating the contact when the trigger is pulled.

Figure 3 is a view showing the means for closing the circuit between rifle and target.

Figure 4 is a view showing general assembly of rifle and target.

Figure 5 is a plan view of the contact plate.

Figure 6 is a view of the target, and

Figure 7 is a circuit diagram.

Figure 8 is a fragmentary front elevation partly in section of the actuating mechanism of the contact point and plate.

According to this invention, the rifle 5 is a dummy, in that it is not adapted to carry live ammunition, said rifle 5 being yieldingly supported on a frame work of a height to comfortably allow of operation.

The rifle is approximately complete in detail in that it possesses a barrel 6, stock 7, trigger 8 and sights 9, therefore, the performer has all the necessary impediments to convey the impression of actual target practice.

As has been previously explained, the rifle 5 is supported on a frame which is preferably enclosed by a sheet metal cover 10 to afford protection for the mechanism associated with the rifle and target, while a rigid bar 10a is secured to the frame 10 whereby jolting or rough usage will not injure the rifle 5 or the mechanism associated therewith.

The rifle 5, at a point near the point of balance, is carried on a universal joint 11 of any suitable character and depending therefrom is a rod 12 which engages at the end with a horizontal bar 12a which carries means for supporting a spring or yielding contact point.

By mounting the arm 12 described on a universal joint radial movement is provided therefor, such movement being necessary in order to sweep over the contact plate and engage with any of contacts thereon.

As has been explained, the arm 12, at its lower end, engages with a substantially horizontal bar 12a which carries ball and socket members 15 and 16, the member 15 being mounted to a cross bar 17 rigidly secured to the casing 10 enclosing the mechanism.

The ball member 16 is disposed upon a block 18 which is slidable upon guide rods as 19, the upper ends of which are secured in the flange 20 of the socket member 21 while the lower ends of the said rods 19 are mounted in the member 22a, the said rods passing through the member 22 which is pivotally mounted in the transverse bars 23, 24 mounted in slotted bars as 24a.

Supported by means of the rods 19 depend-

ing from the block 18 is a contact point 25 which is hinged at 26 to the member 27 comprising a foot plate of any suitable dimensions.

- 5 The action is such that when the rifle 5 is moved to line on the target, the bar 12 is moved accordingly which causes the bar 12a to be moved, and, consequently, the ball and socket members 15 and 16 are rocked, the 10 member 16 using the block 22 as a fulcrum causes the contact point 25 to sweep over the contact plate 28.

The rifle mechanism comprises a pivoted plate 29 with a spring 30 mounted behind 15 same as shown, a pusher rod 31 mounted so as to be withdrawn by the lever 32, a spring 33 being disposed as shown on the upper end of the lever extension 34, a pin 35 being disposed as shown to guide the said pusher 20 rod 31 while a coin slot 37 is arranged approximately between the ends of the pivoted plate 29 and pusher rod 31 respectively.

Depending from the pivoted plate 29 is a 25 rod 38 which connects a substantially horizontal bar 39 pivoted at 40 to a plate 41, the bar 39 having a weight 42 at one end and a pivoted connecting rod 43 at the other, said rod 43 having a piston or plunger 44 at the lower end, said piston 44 moving in a cylinder 45 secured to the said plate 41, said cylinder being filled or partly filled with oil or the equivalent, the object of this arrangement being to retard the opening of the circuit and so keep the particular lamp alight for 30 a sufficient time to enable the score being ascertained.

Disposed above and adjacent to the bar 39 is a contact pin 46 mounted in a support 47 in the form of a cylinder, a spring 48 40 being disposed as shown, whereby the contact pin 46 is maintained in the required position relative to the bar 39.

Disposed upon the front of the casing or cover 10 is a handle 49 which is cranked as at 45 50, said crank connecting a rod 51 which, at its lower end, connects a bar or rod 52 which is pivoted at 53, the outer end of said rod or bar 52 engaging with the ends of the bars 23, 24 disposed in slotted bars as 24a in order 55 that same will be raised or lowered upon the movement of the handle 49 to increase or decrease the throw of the contact point 25 by moving the fulcrum point which is the block 22, and so govern the amount of skill necessary to obtain the maximum number of scoring shots.

Disposed below the contact point 25 is the contact plate 28 which comprises a plurality of insulated sections 54 in the centre 60 of sections 55, 56, 57 and 58.

Above the said contact plate is a terminal block 59 provided with a plurality of terminals 60 which receive the leads from the sections of the contact plate described, each 65 terminal connecting a lamp in the target,

said lamps being arranged in series and connecting one side of a battery 61 through a switch 62, the contact point 25 connecting the other side of the battery 61 via a switch which actually is the contact mechanism comprising 70 the bar 39 and spring controlled contact pin 46, this contact being normally open as will be explained.

The terminal block 59 has its terminals 60 connected to a similar terminal block 63 75 disposed below the target 64, by means of wire connections as 65 which engage with the front of the board 63 as shown, the leads 66 connecting the terminals with the target 64 each wire connecting a lamp.

When a coin or token is inserted in the slot 37, it falls into the position shown in Figure 2, when, on the operation of the lever 32 to set the trigger 8, the pusher rod 31 is withdrawn which allows the coin or token to take 85 the position shown at 32a.

On the trigger 8 being pulled, the pusher rod 31 is moved forwardly, forcing the coin or token forwardly also, which impinges on the pivoted plate 29 and raises same, and the coin or token drops down the chute 67a and 90 into the receptacle 68.

When the pivoted plate 29 is raised, the rod 38 lifts the bar 39 and contact is made between the said bar 39 and contact pin 46 95 which is connected to one side of a battery system, the bar 39 being connected to the contact point 25 disposed above the contact plate 28.

When contact is made as above described, 100 the particular lamp on the target is lit since each insulated contact section is connected to a lamp.

The lifting of the bar 39 causes the plunger 44 to be forced into the oil in the cylinder 105 45 and the withdrawal of the said plunger 44 from the oil by the weight 42, permits of a time lag being established of sufficient duration to enable the score being ascertained.

By altering the sweep of the contact point 110 25 so the difficulty of accurate aim is governed, the means for accomplishing this comprising the handle 49 which is cranked at 50, the operation of which causes the pivoted member 22 being raised or lowered as has 115 been explained.

When the performer by chance selects the centre contact of the contact plate, he will see, on pulling the trigger, that a "bull" is registered and similarly any contact selected 120 by the user, sighting according to his wishes, so a corresponding light will show on the target.

A switch 67 may be included in the lamp circuit as shown in Figure 7 to enable the 125 lamp circuit being thrown out of operation if desired.

The target may be divided into any number of compartments and "inners" and "outers" may be provided for and, furthermore, 130

according to the "hit" made, so a number will go up, either on the face of the target or adjacent thereto, thus a "bull" would count 100, an "inner" say 75 and so on, thus a competitive spirit may be encouraged.

5 We do not wish to be arbitrarily confined to details but desire it to be understood that various improvements and modifications may be embodied without departing from the spirit and scope of the invention.

10 What I claim as my invention and desire to secure by Letters Patent is:—

1. In dummy rifle apparatus, token or coin freed mechanism incorporated with the trigger of the rifle, a bar depending from said rifle, said bar connecting a substantially horizontal bar carrying ball and socket assemblies one of which is mounted on a transverse bar secured to the casing enclosing the mechanism, the other ball and socket member being mounted on a plate disposed above a pivoted plate mounted in bars adjustably supported in a slotted frame, guide rods connecting the flanges of the ball and socket housing, and passing through said plate, and the pivoted plate to connect a plate supporting a sweeping contact mounting which comprises a hinged extension carrying the contact point at the outer and lower end thereof 25 as described.

2. In dummy rifle apparatus as claimed in claim 1, a dummy rifle having incorporated therewith coin freed mechanism, comprising a slot in the rifle adjacent a pivoted plate and 30 pusher bar or rod, a spring pressing on said plate, and a spring connecting the pusher bar, a lever to said rifle for setting the trigger and to withdraw the pusher bar rearwardly and thereby allow a coin or token 35 falling between the end of the said bar and pivoted plate, whereby on the said trigger being pulled, the coin impinges on the said pivoted plate to raise same, and cause a rod connecting a pivoted bar to raise and make 40 contact with a contact pin connecting one side of a battery, said pivoted bar electrically connecting a contact plate disposed below a sweeping contact point actuated by a depending arm from the said rifle as specified.

45 3. In dummy rifle apparatus as claimed in claim 1, a dummy rifle incorporating coin freed mechanism wherein on a coin being inserted in a slot in the rifle and the trigger thereof set and pulled, the circuit between a sweeping contact point, a contact plate and a lamp disposed in a target will be closed and the lamp illuminated to indicate the nature or result of the "shot".

50 4. In dummy rifle apparatus as claimed in claim 1 a rifle incorporating token or coin free mechanism with the trigger thereof, an actuating bar depending from said rifle and connecting a substantially horizontal bar 55 carrying a contact point, a cranked handle

connecting said substantially horizontal and pivoted bar by means of a connecting bar, engaging said horizontal bar at its outer end with a pivoted plate disposed in transverse bars, adapted to move in slotted side bars, 70 whereby on raising or lowering the pivoted plate by turning the cranked handle, the pivot point of the member carrying the contact is adjusted to increase or decrease the sweep of the said contact point over the contact plate as specified.

5. In dummy rifle apparatus as claimed in claim 1, a dummy rifle mounted to permit it being rocked or moved in relation to a target, said rifle incorporating a pivoted plate and 80 pusher bar mounted adjacent a coin or token slot, springs to the pivoted plate and to the pusher bar which is actuated by a lever for setting the trigger, a bar or rod depending from the said rifle, a substantially horizontal bar or rod connecting the said depending bar or rod, said horizontal bar or rod engaging ball and socket members, one of which is mounted on a transverse bar and the other supporting a sweeping contact point which 85 is hingedly mounted to a foot disposed on the lower end of guide rods passing through a pivoted block disposed between vertically adjustable bars, the said rods engaging with the flanges of the said ball and socket member, means for adjusting the swing or sweep 90 of the contact point comprising a cranked handle mounted on the casing of the mechanism, said crank pivotally connecting a rod which at its lower end connects a pivoted bar 95 or rod, the outer end of which engages with the pivoted block in the vertically adjustable bars, a contact plate below the sweeping contact point, said contact plate comprising a plurality of insulated sections, each of which electrically connects a terminal on a terminal block, wires from the terminal block to a terminal block adjacent a target comprising a plurality of lamps in series, a battery system for lighting the lamps when contact is made, 100 by pulling the rifle trigger which causes a coin or token to be forced forwardly by a pusher bar to lift a pivoted plate having a rod thereto which raises a pivoted bar to make contact with a yielding contact pin connected to one side of a battery, means for retarding the breaking of contact between the pivoted bar and yielding contact pin comprising a plunger mounted to the outer end of the said pivoted bar, said plunger operating 105 in a cylinder containing a quantity of oil, a weight to the opposite end of the said pivoted bar and a coin chute and receptacle to the apparatus as described.

Signed at Melbourne, Victoria, Australia, 125 this 2nd day of April A. D. 1930.

ERNEST ALFRED BOWLER.
